UNITED STATES PATENT OFFICE.

MAYNARD W. SCOTT, OF ROZEL, KANSAS.

ANIMAL-EXTERMINATOR.

1,174,904.

Specification of Letters Patent. Patented Mar. 7, 1916.

Application filed February 24, 1915. Serial No. 10,326.

To all whom it may concern:

Be it known that I, MAYNARD W. SCOTT, a citizen of the United States, residing at Rozel, in the county of Pawnee and State of Kansas, have invented new and useful Improvements in Animal-Exterminators, of which the following is a specification.

This invention is an improved apparatus for generating smoke, gases, or noxious vapors and forcing the same into the holes of burrowing animals such as gophers, prairie dogs, and also for forcing such smoke or vapors into hollow trees, logs or the like for expelling or killing the animals therein, the object of the invention being to provide an improved apparatus of this kind which is cheap and simple, is not likely to get out of order, is very efficient and may be readily used.

The invention consists in the construction, combination and arrangement of devices hereinafter described and claimed.

In the accompanying drawings: Figure 1 is a vertical sectional view of an animal exterminator constructed in accordance with my invention. Fig. 2 is a detail sectional view.

In accordance with my invention I provide a base 1 on which is a tank or fire box 2 and a pump 3, the pump and fire box being spaced apart and the base being provided with a bore 4, which communicates with the lower ends of the fire box and pump and at the outer end of which is a nozzle 5 to which a hose may be attached so that the other end of the hose may be inserted in a burrow in the ground or a hollow in a log, tree, or the like.

The fire box is provided with a removable cover 6 and is also provided near its bottom with a screen 7 which serves as a grate. An opening 8 is in the bottom of the fire box to establish communication between the fire box and the bore, and a downwardly opening spring valve 9 is arranged in said opening and is adapted to normally close the same.

The pump is an upright cylinder in which is arranged a piston or plunger 10 which has an upwardly extending operating rod 11, provided with a handle 12 at its upper end. In the lower end of the pump cylinder are openings 13, 14 which communicate with the bore 4 and are respectively provided with a downwardly opening valve 15 and an upwardly opening

valve 16. A dividing member 16' divides the bore of the base into individual compartments 17' and 18', the opening 14 opening out into the compartment 18' of the bore 4 of the base while the opening 13' opens out into the compartment 17' of the bore of the base.

In the operation of my improved animal exterminator rags or other material which when burned will give off a thick smoke or generate a noxious gas or vapor, are placed in the fire box together with coals, or other fuel, and the cover 6 is then secured. The pump is then operated. On each up stroke of the pump or piston the valve 9 opens together with the valve 16 so that smoke or vapor or gas is drawn from the fire box through the bore 4 and into the pump below the piston, and on each down stroke of the piston, said valves 9 and 16 close, and the valve 15 opens, so that the smoke, gas, or vapor is forced by the pump through the nozzle and hose and into the burrow or hollow log, thereby either expelling or killing the animal or animals therein.

Having thus described my invention I claim:—

1. An animal exterminator comprising a base having a bore and nozzle at the outer end of the bore, a fire box on the base having an opening in its bottom communicating with the bore and provided with a downwardly opening valve, an upright pump cylinder also on the base and disposed in spaced parallelism with the fire box and having openings at its lower end communicating with the bore, and one provided with a downwardly opening valve and the other with an upwardly opening valve, a pump or plunger arranged in said cylinder and provided with operating means, and a screen in said fire box and disposed above its valve and serving as a grate for the fire box and also serving to prevent the fuel contained in the fire box from contacting with such valve and causing the opening thereof.

2. An animal exterminator comprising a base having a bore, a dividing member in the bore and forming compartments, a fire nozzle at the outer end of the bore, a fire box on the base having an opening in its bottom communicating with one of the compartments, and provided with a downwardly opening valve, an upright pump cylinder also on the base and having openings at its lower end opening out in both of the compartments.

parts of the bore and communicating therewith, and one of the openings being provided with a downwardly opening valve and the other with an upwardly opening valve, a pump or plunger arranged in said cylinder and provided with operating means, and a screen in said fire box and disposed above its valve and serving as a grate there-

for and preventing the fuel contained in the fire box from contacting with such valve.

In testimony whereof I affix my signature in presence of two witnesses.

MAYNARD W. SCOTT.
